(57) **CLAIM**

The ornamental design for an essential oil cotton pad as shown and described.

DESCRIPTION

FIG. 1 is a perspective view of an essential oil cotton pad showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the essential oil cotton pad shown in an environment of use installed in a massager device.

The evenly spaced broken lines depict portions of the essential oil cotton pad form no part of the claimed design. The dot-dashed broken lines depict the boundary of the claim and forms no part of the claimed design. The broken line showing of a massager device in FIG. 8 depicts environment and forms no part of the claimed design.

1 Claim, 6 Drawing Sheets
